United States Patent Office

Des. 195,394
Patented June 11, 1963

195,394

SIGN

Jack Levit, 437 Semple Ave., West Kildonan,
Manitoba, Canada

Filed Nov. 24, 1961, Ser. No. 67,675

Term of patent 14 years

(Cl. D1—12)

I claim:

The ornamental design for a sign, as shown and described.
